CONCENTRATION OF FAT-SOLUBLE VITAMINS

Edgar M. Shantz, Rochester, N. Y., assignor to
Distillation Products, Inc., Rochester, N. Y., a
corporation of Delaware

No Drawing. Application January 21, 1944,
Serial No. 519,203

10 Claims. (Cl. 167—81)

1

This invention relates to improved procedure for the concentration of fat-soluble vitamins and in particular for the concentration of vitamin A contained in fish liver oils, and fractions thereof.

This invention has for its object to provide improved procedure for the concentration of fat-soluble vitamins. Another object is to provide improved procedure for the concentration of vitamins contained in fish liver oils and distillates or fractions thereof, and in particular for the concentration of vitamin A contained in such oils or fractions. Other objects will appear hereinafter.

These and other objects are accomplished by my invention which includes reacting a glyceride fat which contains a fat-soluble vitamin with a member of the group consisting of primary amines, secondary amines, and quaternary ammonium bases, and then separating the fat-soluble vitamin from the reaction products.

In the following examples and description, I have given several of the preferred embodiments of my invention, but it is to be understood that these are set forth for the purpose of illustration and not in limitation thereof.

The amine, or ammonium base, which is used must be one which will substantially completely react with the glyceride oil under the conditions of treatment. Primary amines are preferred since they react with the glyceride oil with relative rapidity. Secondary amines react somewhat more slowly but can be used satisfactorily. Quaternary ammonium bases may be used but tertiary amines are unsatisfactory. Substituted amines, or ammonium bases, such as hydroxy, halide, etc., amines can be used and are to be understood as being included within the expressions "primary amines," "secondary amines," and "quaternary ammonium bases" as used herein and in the claims.

The reaction takes place over a relatively wide range of temperature. The preferred range is about 80° to about 150° C. For most purposes a temperature of about 100° C. is quite satisfactory. Too high a temperature causes decomposition of the more labile vitamins whereas low temperatures decrease the rate of reaction.

The time of reaction depends upon factors such as concentration of the reactants, the temperature, and the particular ammonium derivative used. In most cases the reaction requires from about two to twenty hours.

At least one molecular equivalent of amine should be used based on the fatty acid content of the glyceride treated if complete removal of the

5 fat is required. It is more practical and preferred to use a slight excess. To speed up the reaction, from two to ten molecular equivalents of amine may be used for a given amount of oil. Excess reagent may, of course, be recovered and used again. It is also preferred to carry out the reaction in an inert atmosphere such as carbon dioxide or nitrogen.

If a diamine is used, it can be made to react 10 with two molecules of fatty acid to yield a di- amide. One method of doing this is to use just enough of the diamine or polyamine to provide one $-\text{NH}_2$ group for each fatty acid radical present in the fat which contains the vitamin. Another method is to react a given quantity of fat 15 with an excess of the diamine, after which the excess unused diamine is removed and the reaction product is then allowed to react with another equal quantity of the same oil or fat.

20 If it is desired, the reaction products may be treated with an esterifying agent such as acetic anhydride or acetyl chloride before distillation, solvent extraction, or filtration of the desired "unsaponifiable" fraction in order to form vitamin esters. Such a reagent would also react with certain of the fatty acid substituted amides, as will be shown below. This is desirable in certain cases to decrease their solubility.

The following empirical formulas are for the 25 purpose of illustrating and clarifying the reactions described above. Specific examples are given later.

1. Reaction of an oil with a primary amine, R'' NH_2 :

2. Reaction of oil with a hydroxy amine, such 40 as ethanolamine:

3. Reaction of above products with esterifying 45 agent such as acetyl chloride:

3

4. Reaction of oil with an excess of a polyamine such as ethylenediamine:

5. Reaction of above products with another equal amount of oil:

6. Reaction of products of illustration 4 with an esterifying agent such as acetyl chloride:

7. Reaction of two equivalents of oil with a polyamine such as ethylenediamine:

8. Reaction of an oil with a quaternary ammonium base:

The esters of other valuable substances such as vitamin A, vitamin D, sterols, etc., occurring in the oils react in an analogous manner to give the free alcohols. These are shown empirically in the following formulae where ROH stands for the alcohol, such as vitamin A.

1a. Reaction of vitamin esters with a primary amine, R'NH₂:

2a. Reaction of vitamin esters with a hydroxy amine, such as ethanolamine:

3a. Reaction of above products with esterifying agent such as acetyl chloride:

4a. Reaction of vitamin esters with an excess of a polyamine such as ethylenediamine:

5a. Reaction of above products with another equal amount of oil:

6a. Reaction of products of illustration 4 with an esterifying agent such as acetyl chloride:

4

7a. Reaction of two equivalents of vitamin esters with a polyamine such as ethylenediamine:

8a. Reaction of vitamin esters with a quaternary ammonium base:

10 The following are specific examples of the methods outlined above.

Example 1

190 grams of fish liver oil distillate containing 210,000 units per gram of vitamin A ester were heated at 100° C. under nitrogen for twenty hours with 700 cc. of ethanolamine. At the end of this time the excess ethanolamine was removed under reduced pressure. The product was a waxy solid at room temperature but became completely liquid at 50° to 60° C. 183 grams of this material were distilled in a cyclic molecular still. A fraction weighing 32.2 gms. was obtained which distilled between 100° and 140° C. at a pressure of 3 to 10 m_μ. This fraction, a light yellow oil which became solid at room temperature, contained 900,000 units per gram of vitamin A alcohol.

Example 2

30 230 grams of fish liver oil distillate containing 200,000 units per gram of vitamin A ester were heated for 15 hours at 100° C. under nitrogen with 320 grams of ethanolamine. After removal of the excess ethanolamine under reduced pressure, the residual product was distilled in a cyclic molecular still. The fraction distilling between 100° C. and 145° C. at a pressure of 3 to 10_μ weighed 52 grams and contained 610,000 units of vitamin A alcohol per gram.

40 This distillate was then dissolved in 200 cc. of methyl alcohol and chilled to -60° C. to freeze out the fatty acid ethanolamides which had distilled with the vitamin A. After filtration in the cold, the methyl alcohol was evaporated and the residue was found to consist of 20 grams of a dark red oil containing 1,300,000 units of vitamin A per gram.

Example 3

50 150 grams of fish liver oil distillate containing 200,000 units of vitamin A per gram were heated for 16 hours at 100° C. under nitrogen with 450 cc. of ethanolamine. After removal of the excess ethanolamine by distillation under reduced pressure, the residue was taken up in 1.5 liters of warm ethyl ether. About 30% of the material was insoluble at room temperature and was filtered off. The filtrate was chilled to 5° C. and again filtered. The ether was removed, the residue dissolved in 500 cc. of methyl alcohol, and chilled to -35° C. After filtration the methyl alcohol was evaporated and the residue was found to contain 54 grams of dark red oil having a potency of 508,000 units of vitamin A per gram.

Example 4

70 200 grams of fish liver oil distillate containing 200,000 units per gram of vitamin A were heated for 12 hours with 300 grams of 1-amino-2-butanol at 100° C. under nitrogen. The excess amine was removed under reduced pressure and the residual product distilled in a cyclic molecular still. Four fractions weighing a total of 155 grams were removed between 100° C. and 160° C.

The largest fraction had a potency of 353,000 units of vitamin A per gram.

Example 5

200 grams of fish liver oil distillate containing 200,000 units per gram of vitamin A were heated for 12 hours at 100° C. under nitrogen with 275 grams of 2-amino-2-ethyl-1, 3-propanediol. The entire mixture was placed in the molecular still and the excess amine removed at 100° C. at a pressure of about 1 mm. The pressure was then reduced to 5-10 μ , and the temperature raised to 140° C. A distillate with a vitamin A potency of 400,000 units per gram was obtained.

Example 6

275 grams of fish liver oil distillate were heated for five hours at 100° C. with 275 grams of ethylene diamine. The excess ethylene diamine was removed under reduced pressure, and the residue distilled in the molecular still. The distillate had a potency of 363,000 units per gram of vitamin A.

Example 7

110 grams of fish liver oil distillate containing 200,000 units of vitamin A per gram were heated under nitrogen for 10 hours at 100° C. with 100 grams of ethylene diamine. The excess diamine was removed under reduced pressure and 110 grams more of the fish liver oil were added to the residue. This mixture was heated for another twenty hours under nitrogen after which it was distilled in a molecular still. The product remained liquid only if heated to about 100° C. A distillate was obtained between 100° and 160° C. which was a viscous orange oil containing 570,000 units per gram of vitamin A.

Example 8

150 grams of fish liver oil distillate containing 200,000 units per gram of vitamin A were heated at 100° C. with 150 grams of ethylene diamine for 15 hours. The excess diamine was removed under reduced pressure and the residue dissolved in one liter of acetone. 100 grams of pyridine, followed by 100 grams of acetic anhydride, were added. Upon cooling, the fatty acid-acetic acid diamides of ethylene diamine crystallized out and were filtered off. Ethyl ether was added to the filtrate and the solution washed several times with water. Upon evaporation of the ether, 68 grams of residue remained which contained 358,000 units per gram of vitamin A acetate.

Example 9

30 grams of fish liver oil distillate (200,000 units per gram), 30 cc. of tetraethanolammonium hydroxide (40% aqueous solution) and 30 cc. of ethyl alcohol were refluxed for 2 hours under nitrogen. The mixture was dissolved in ether, washed three times with water to remove the reaction products which are soluble in water and the ether removed by evaporation. The residue consisted of 12 grams of red oil which contained 465,000 units per gram of vitamin A alcohol.

Example 10

270 gms. of fish liver oil distillate containing 186,000 units of vitamin A per gram were heated at 80° C. for 15 hours with 160 gms. of aminoethylethanolamine under a stream of nitrogen. The reaction mixture was then placed in a molecular still and distilled. The first fraction, removed at 100° C. at a pressure of 1 mm., con-

tained mainly glycerol and excess aminoethyl-ethanolamine. The fraction distilling between 120 and 140° C. at a pressure of 15 microns consisted of a light yellow solid having a vitamin A potency of 510,000 units per gram.

Example 11

560 gms. of soupfin shark liver oil distillate having a vitamin A potency of 213,000 units per gram were heated with 125 gms. of ethanolamine for 16 hours at 80° C. under nitrogen. The reaction mixture was then dissolved in 2.5 liters of acetone and the fatty acid ethanolamides filtered off after successively chilling the mixture to 0° C., -35° C., and -50° C. The solvent was then removed from the filtrate under reduced pressure and the residue distilled in a molecular still. The fraction distilling between 110° and 135° C. contained vitamin A alcohol at a potency of 620,000 units per gram.

Example 12

600 gms. of fish liver oil having a vitamin A potency of 27,000 units per gram were heated under nitrogen for 16 hours at 80° C. with 100 gms. of ethanolamine. The reaction mixture was dissolved in 3 liters of warm acetone. This solution was cooled to -15° C. and the solid material filtered off, washing with 500 ml. of chilled acetone. The filtrate was then chilled to -50° C. and again the solids which separated were filtered off as before. The solvent was removed from the filtrate by distillation and the residue distilled in a molecular still. The main fraction contained 416,000 units per gram of vitamin A.

Example 13

600 gms. of a high vacuum distillate of deodorizer scum containing 24% tocopherol were heated for 12 hours at 80° C. with 100 gms. of ethanolamine. 3.0 liters of acetone were added to the reaction mixture. The solution was then chilled to -50° C. and the separated solids filtered off. The solid material was dissolved in 2 liters of fresh acetone and again the solids were removed by filtration after chilling to -50° C. The filtrates were combined and the acetone removed by distillation. The residue was distilled in a molecular still. The fraction distilling at 150° C. contained 25% of the starting tocopherol at a concentration of 50%. The fraction distilling at 170° C. contained 45% of the original tocopherol at a concentration of 72.5%.

Example 14

400 gms. of a high vacuum distillate of deodorizer scum containing 18% tocopherol were heated at 80° C. for 15 hours with 70 grams of ethanolamine. The reaction mixture was dissolved in 2 liters of acetone and the solid material removed by filtration after chilling first to -20° C., then to -50° C. The acetone was distilled from the filtrate and the residue dissolved in 1 liter of ethyl ether. The ether solution was washed three times with 1NHCl, followed by two water washes. This washing was found to improve the taste of the final product considerably. The ether was then removed by distillation. The residue then contained 50.3% tocopherol. Upon distillation 75% of this tocopherol was obtained at a concentration of 70% or better.

The vitamin can be separated from the reaction product in any desired manner. I prefer to use vacuum distillation, and in particular, high-vacuum, unobstructed path or molecular distillation. However, solvent extraction and filtration

or pressing of the reaction products may be used. Combinations of these separation procedures can be used.

While the procedure of my invention is of particular advantage for the concentration or separation of vitamins, it can also be used to separate or concentrate sterols as well as like materials which are present in fats and which do not react with the amines or like compounds disclosed herein.

What I claim is:

1. The process of preparing a fat-soluble vitamin concentrate which comprises reacting a glyceride fat which contains a fat-soluble vitamin with at least approximately stoichiometric amounts of a member of the group consisting of primary amines, secondary amines, and quaternary ammonium bases, until substantially all the fatty acids of the glyceride have combined therewith and then separating the vitamin in concentrated form from the reaction mixture.

2. The process of preparing a fat-soluble vitamin concentrate which comprises reacting a glyceride fat which contains a fat-soluble vitamin with at least approximately stoichiometric amounts of a primary amine, until substantially all the fatty acids of the glyceride have combined therewith and then separating the vitamin from the reaction mixture.

3. The process of preparing a fat-soluble vitamin concentrate which comprises reacting a glyceride fat which contains a fat-soluble vitamin with approximately stoichiometric amounts of a member of the group consisting of primary amines, secondary amines, and quaternary ammonium bases at a temperature of between about 80° and 150° C. until substantially all the fatty acids of the glyceride have combined therewith, and then separating the vitamin from the reaction mixture.

4. The process of preparing a fat-soluble vitamin concentrate which comprises reacting a glyceride fat which contains a fat soluble vitamin with at least approximately stoichiometric amounts of a primary amine at a temperature of between about 80° and 150°, until substantially all the fatty acids of the glyceride have combined therewith, and then separating the vitamin from the reaction mixture.

5. The process of preparing vitamin A concentrate which comprises reacting a glyceride fat derived from a fish which contains vitamin A with at least approximately stoichiometric amounts of a member of the group consisting of primary amines, secondary amines, and quaternary ammonium bases, until substantially all the fatty acids of the glyceride have combined therewith and then separating the vitamin A in concentrated form from the reaction mixture.

6. The process of preparing vitamin A concentrate which comprises reacting a glyceride fat derived from a fish which contains vitamin A with at least approximately stoichiometric amounts of a member of the group consisting of primary amines, secondary amines, and quaternary ammonium bases, until substantially all the fatty acids of the glyceride have combined therewith and then subjecting the reaction mixture to high-vacuum unobstructed path distillation and separating a vitamin A concentrate as a distillate.

7. The process of preparing a fat-soluble vitamin concentrate which comprises reacting a glyceride fat which contains a fat-soluble vitamin with 1 to 10 molecular equivalents of a member of the group consisting of primary amines, secondary amines, and quaternary ammonium bases, until substantially all the fatty acids of the glyceride have combined therewith and separating the vitamin from the reaction product.

8. The process of preparing a fat-soluble vitamin concentrate which comprises reacting a glyceride fat which contains a fat-soluble vitamin with at least approximately stoichiometric amounts of a member of the group consisting of primary amines, secondary amines, and quaternary ammonium bases until substantially all the fatty acids of the glyceride have combined therewith at a temperature of about 100° for a period of time between about 2 to 20 hours, and then separating the vitamin from the reaction product.

9. The process of preparing a fat-soluble vitamin concentrate which comprises reacting a glyceride fat derived from a fish and containing a fat-soluble vitamin with 1 to 10 molecular equivalents of a primary amine until substantially all the fatty acids of the glyceride have combined therewith at a temperature of about 100° for a period of time between about 2 to 20 hours, and separating a vitamin in concentrated form from the reaction products.

10. The process of preparing a concentrate of a substance selected from the group consisting of fat soluble vitamins and sterols present in a natural glyceride fat which substance does not react with amines or quaternary ammonium bases which process comprises reacting the fat with at least approximately stoichiometric amounts of a member of the group consisting of primary amines, secondary amines and quaternary ammonium bases until substantially all the fatty acids of the glyceride have combined therewith and then separating said substance in concentrated form from the reaction mixture.

EDGAR M. SHANTZ.
